(57) **CLAIM**

The ornamental design for a bottle, as shown and described.

DESCRIPTION

FIG. 1 is a front perspective view of a bottle according to the present invention.

FIG. 2 is an elevation view of the bottle illustrated in FIG. 1.

FIG. 3 is another elevation view of the bottle illustrated in FIG. 1.

FIG. 4 is another elevation view of the bottle illustrated in FIG. 1.

FIG. 5 is another elevation view of the bottle illustrated in FIG. 1,

FIG. 6 is a bottom plan view of the bottle illustrated in FIG. 1.

FIG. 7 is a top plan view of the bottle illustrated in FIG. 1.

FIG. 8 is an exploded perspective view of the bottle illustrated in FIG. 1 showing a cap portion thereof separated from a body portion thereof, and a roller applicator.

FIG. 9 is an exploded perspective view of the bottle illustrated in FIG. 1 showing a cap portion thereof separated from a body portion thereof, and a squeeze top applicator; and,

FIG. 10 is an exploded perspective view of the bottle illustrated in FIG. 1 showing a cap portion thereof separated from a body portion thereof, and an open top.

The broken lines in the drawings are for illustrative purposes and form no part of the claimed design.
